W. M. Baker

UNITED STATES PATENT OFFICE.

W. M. BAKER, OF WALPOLE, INDIANA.

CAR-SEAT AND COUCH.

Specification of Letters Patent No. 22,693, dated January 25, 1859.

To all whom it may concern:

Be it known that I, W. M. BAKER, of Walpole, in the county of Hancock and State of Indiana, have invented a new and 5 Improved Combined Car-Seat and Couch; and I do hereby declare that the following is a full, clear, and exact description of the same, reference being had to the annexed drawings, making a part of this specification, in which—

Figures 1 and 2, are vertical central sections of my invention, the planes of section crossing each other at right angles.

Similar letters of reference indicate corresponding parts in the two figures.

To enable those skilled in the art to fully understand and construct my invention I will proceed to describe it.

A, represents the body of a car, provided 20 with my improvement, which is placed at the center of the car leaving a passageway a, at each side as shown clearly in Fig. 2.

B, represents a seat supported by legs b, and being about double the length of the 25 usual seats in order to accommodate four instead of two passengers. The seat B, may be upholstered in the usual way and at each end of the seat a vertical rod C, is attached, said rods extending from the bottom to the 30 top of the car as shown plainly in Fig. 2.

D, is the back of the seat B, this back may be of usual construction and is attached to the rods C, C, by arms e, e, which are pivoted to the rods as shown at d. The back 35 D, may be reversed or turned to face in either direction precisely the same as the ordinary reversible backs, and to each rod C, a curved bar e, is attached having stops f, at each end to support the arms.

Underneath the seat B, an upholstered 40 slide E, is placed. This slide is provided with legs g, and its ends when underneath the seat, rest on ways h, attached to the inner sides of the legs b, of the seat B.

F, represents an upholstered board or 45 plane which corresponds in area to the seat B. To each end of the board F, arms i, are attached, said arms being of the same form as those attached to the ends of the ordinary car seats. To the upper part of each arm i, a projection j, is attached, and the rods C, pass through said projections which are allowed to slide freely on the rods. To the under side of the board F, folding rods 50 or legs k, are attached, and to the front and back sides of the board F, fenders or guards

l, are hinged or jointed as shown at m, so that said fenders or guards may be folded underneath the board and secured thereto by a catch n, or be raised and secured in 60 a vertical position by catches o, attached to each side of the board F.

G, is an upholstered board, which may be constructed precisely similar to the board F. The board G, is provided with end plates p, p, having guides q, attached to their outer sides through which the rods C, C, pass. The board G, is provided with fenders or guards r, which are arranged precisely similar to the fenders or guards l, 70 to the board F.

To the outer side of the back D a roller s, is attached, said roller having one end of a curtain H, attached to it. To the top of the car and at the outer side of each rod C, 75 a roller t, is placed, said rollers having one end of curtains u, attached. The opposite ends of the curtains u, are connected by a rod I, and each roller t, has a weight v, attached to it by a cord w, the weights being fitted in vertical boxes x, attached to the sides of the car, see Fig. 2. To the outer end of the curtain H, cords y, are attached and these cords are connected to drums z, at one end of the rollers, the cords 80 of the weights v, are attached to the same drums but are wound upon them in reverse directions.

When the invention is used as a day seat, the board F, has its legs k, folded beneath 90 it, and also the fenders or guards l, l, the legs being secured in a folded position by catches l', and the fenders or guards by the catch n, and said board rests on the seat B, and strictly speaking forms the seat. The 95 slide E, is shoved underneath the seat B, and the board G, is elevated to the upper parts of the rods C, C, and retained near the top of the car by spring catches o'. The curtains u, u, are rolled up on the 100 rollers t, t, and the curtain H, is rolled on the roller s. When the several parts are in the position as above described, a day seat is obtained, equally as convenient and desirable in every respect as the ordinary day 105 car seats. In order to obtain sleeping couches, the slide E, may be first withdrawn from underneath the seat B, the board F, may then be raised the legs or rods B, unfolded and their lower ends placed on the 110 edges of the seat B, the fenders or guards l, being turned up and secured in a vertical

position by the catches *o*. The rods or legs *k*, support the board *F*, at a suitable height above the seat *B*. The board *G*, is then moved down between the rods *C*, and is retained at a suitable height above the board *F*, by catches *b*, in the rods *C*, the fenders or guards *r*, being turned up in a vertical position. The curtains *u*, *u*, are then drawn down by grasping the rod *I* which is secured to the floor of the car by a catch *c*. As the curtains *u*, *u*, are drawn down the curtain *H*, is raised. From the above description it will be seen that four sleeping couches are obtained, *B*, and *E*, being side by side and *F*, and *G* elevated between the rods *C*, *C*, one above the other in the same plane with *B*. The couches also it will be seen are inclosed by the curtains *u*, *u*, *H*, but one curtain *H*, is required for each seat, as one of said curtains divides two seats or serves as a screen for both at one side.

This invention is extremely simple and

efficient. It may be economically applied and readily adjusted so as to form either a day seat or a sleeping couch.

25

Having thus described my invention what I claim as new and desire to secure by Letters Patent, is,

1. The arrangement and combination of the boards *G*, *F*, arms (*i*), curved bar (*e*), 30 legs (*R*), fenders (*l*), slide *E*, seat *B*, and rods *C*, as herein shown and described.

2. The arrangement and combination of the curtain *H*, the seat backs *D*, drums (*z*), weights (*v*) curtains (*u*), and rod *I*, as 35 herein shown and described; so that when the rod *I*, descends, the curtains (*u*) will fall and the curtain *H* rise; and when the rod *I* is released, all the curtains will be simultaneously rolled up.

W. M. BAKER.
